UNITED STATES PATENT OFFICE.

WILLIAM HENRY TROUT, OF MILWAUKEE, WISCONSIN, ASSIGNOR TO ALLIS-CHALMERS MANUFACTURING COMPANY, OF MILWAUKEE, WISCONSIN, A CORPORATION OF DELAWARE.

SAW-MOUNT.

1,251,844.

Specification of Letters Patent. Patented Jan. 1, 1918.

Original application filed March 5, 1910, Serial No. 547,388. Divided and this application filed November 4, 1916. Serial No. 129,904.

To all whom it may concern:

Be it known that I, WILLIAM HENRY TROUT, a citizen of the United States, residing at Milwaukee, in the county of Milwaukee and State of Wisconsin, have invented a certain new and useful Improvement in Saw-Mounts, of which the following is a specification.

This invention relates to improvements in the construction of machines used for trimming the edges of sawed lumber, commonly known in lumber-mills as the edger, and has specific relation to an improvement in saw-mounts for slidably supporting circular saws.

An object of the invention is to provide a saw-mount especially applicable to circular saws, which is simple in construction and efficient in operation. One of the more specific objects is to provide improved means for holding the saws upon the saw-shaft in rigid alinement, while at the same time permitting them to slide freely upon the shaft and to approach closely to one another. Another object is to provide means for lubricating the coating surfaces between the saws and the shaft, whereby the saws may be readily moved along the shaft, and whereby danger of either wasting or sling the lubricant and necessity of frequent reoiling, are eliminated.

The present application is a division of the application from which Patent No. 1,203,940 matured.

A clear conception of an embodiment of the invention may be had by referring to the drawing accompanying and forming a part of this specification, in which like reference characters designate the same or similar parts in the various views.

Figure 1 is a fragmentary plan view of a six-saw edger, showing the saws, the guides, and the gage mechanism, diagrammatically.

Fig. 2 is an enlarged vertical section through a fragment of the saw-shaft, the saw-collars and fragments of the saws, showing the method of mounting.

Fig. 3 is an enlarged transverse vertical section through the saw-shaft and saw-col-

lar, showing also a fragment of a saw, the section being taken along the line III—III of Fig. 2, looking in the direction of the arrows.

Fig. 4 is an enlarged transverse vertical section through the saw-shaft and saw-collar, showing also a fragment of a saw, the section being taken along the lines IV—IV of Fig. 2 looking in the direction of the arrows.

Fig. 5 is an enlarged vertical section through a fragment of a saw and saw-collar, showing also a fragment of the shaft, the elements being rotated through an angle of 45° from the position shown in Fig. 2.

Fig. 6 is an enlarged transverse vertical section through the saw-shaft and saw-collar, the section being taken along the line VI—VI of Fig. 2, looking in the direction of the arrows.

While the invention is disclosed as applied to a single edger, provided with six saws by the way of illustration, it will be understood that the same principles may be applied to double edgers and to any number of saws, without departing from my invention. The invention is, moreover, applicable generally wherever circular saws are drivingly connected with a shaft and are slidable along the shaft.

The edger disclosed, see Fig. 1, comprises essentially a longitudinal saw-shaft 10, mounted in suitable bearings not shown, and supporting a series of circular saws 11. The saws 11 are slidably mounted upon the shaft 10 by means of saw-collars 12, which are drivingly connected with the shaft 10 by means of splines or keys 3, which engage key-ways 9. The saws are shiftable by means of saw-guides 13, supported upon saw-guide carriers 15, which are slidably mounted upon the longitudinal guide-rod 14. The guide-carriers 15 are themselves shifted and set in the desired positions by means of gage-hubs 18, which slide upon a longitudinal gage-rod 17 in the usual manner. The guide-carriers 15 are connected with the gage-hubs 18 by means of oblique bars 16. In the mounting of the saws on the saw-

arbor, the difficulty with previous constructions has been to secure a wide enough mounting while at the same time permitting the saws to come close together. If the 5 saw-collars are made narrow they will soon become loose and wabbly by continuous side-wise shifting. Furthermore, the old form of saw-collar is subject to great difficulty in maintaining proper lubrication, as oil will 10 not readily remain on the shaft when it is turned at a high rate of speed, and if thrown or poured upon the shaft will be scattered by centrifugal force.

In the improved construction of saw-collars, see Figs. 2 to 6 inclusive, the collar 12 is made relatively narrow, this collar being reduced and threaded at the portion 1 to receive a clamping nut 2, which holds the saw 11 firmly in place. The lateral bearing 15 surface upon the shaft 10 is secured by providing two elongated keys 3, which are fixed in the grooves 4 of the collar 12 and slide in key-ways or slots in the shaft 10. The ends of the keys 3 extend beyond the ends of the 20 collars 12 a considerable distance, but preferably not more than half the width of the collar 12. It will be noted from Figs 2 to 25 5 inclusive that four key-ways or slots 9 have been provided in the shaft 10, and that four corresponding grooves 4 are formed in each collar 12, but each collar carries keys 3 in only two diametrically opposite grooves 4 in which the keys are secured by means of screws 5. This enables the keys 3 on any 30 collar 12 to be received in the corresponding aligned grooves 4 of the adjacent collar 12 when the two saws 11 are moved close together so that the keys do not in any way interfere with the approaching of the saws 35 40 until the adjacent ends of the saw-collars 12 abut. It is, of course, realized that while only four grooves have been shown, any other desirable number of grooves may be provided, the principle being that the keys 3 are fixed in one saw-collar 12 in alignment 45 with vacant grooves 4 in adjacent saw-collars 12.

In order to properly lubricate the coacting surfaces of the shaft 10 and saw-collars 50 12 during sliding of the collars along the shaft, the collars 12 are provided with sets of chambers 6 between the grooves 4 thereof, these chambers being packed with oil-saturated waste 7 to which lubricant may be 55 supplied through holes 8, see Fig. 6.

While I have herein shown and described the most improved form of the invention, it should be understood that not all of the features are essential thereto, or necessarily 60 made in the exact form shown, but various changes and modifications may be made without departing from the spirit of this invention, and it is to be understood, therefore, that the invention is not otherwise lim-

ited than by the scope of the appended 65 claims.

It is claimed and desired to secure by Letters Patent:—

1. In combination, a shaft, a saw-collar slidably mounted thereon, a circular saw mounted on said collar, and one or more keys fixed in grooves in said collar and sliding in grooves in the shaft, said key or keys being longer than said collar.

2. In combination, a shaft having two grooves therein, a pair of saw-collars having each two grooves therein, and a pair of keys mounted in the grooves of the respective collars; each key sliding in one of the grooves in the shaft and having an end projecting beyond the saw-collar in which it is fixed and adapted to be received within the vacant groove of the other saw-collar.

3. In combination, a rotating shaft having a longitudinal groove therein, and a pair of saw-collars nonrotatably mounted on said shaft and one of which is slidably mounted on said shaft, said slidably mounted collar having a key sliding in said groove and projecting beyond the end of the collar, and the other collar having a recess adapted to receive the projecting end of said key whereby the two collars are enabled to approach close together.

4. In combination, a rotatable shaft, and a pair of collars nonrotatably mounted thereon, one of said collars being slidably longitudinally on said shaft, one of said collars having one or more laterally projecting elements abutting upon the shaft and adapted to form an extension of the bearing-surface, and the other having one or more recesses adapted to receive said projecting elements or elements.

5. In combination, a rotating shaft, a pair of saw-collars nonrotatably and slidably mounted thereon, each of said collars having one or more laterally projecting elements on the side adjacent to the other collar adapted to form extensions of the bearing-surface of the collars upon said shaft, and each collar having also one or more recesses adjacent to the shaft which are in line with and adapted to receive the projecting element or elements on the other collar, whereby said collars are enabled to approach close together.

6. In combination, a saw-shaft having one or more pairs of longitudinal grooves therein, and a pair of saw-collars slidably mounted on said shaft and each carrying one or more keys which project beyond the collar, each key mounted on one collar engaging in one of the grooves of said shaft and lying opposite to a vacant space on the other collar, whereby it passes under said collar when the two collars are approached.

7. In combination, a saw-shaft having four equally spaced longitudinal grooves therein, a pair of saw-collars slidably

mounted on said shaft and each having four corresponding grooves in their naves, and four keys which are longer than the saw-collars and two of which are mounted in one pair of diametrically opposite grooves in one collar and the other two in the other pair of diametrically opposite grooves in the other

collar, whereby each pair of keys carried by one collar is adapted to be received within the vacant grooves of the other one as said collars are approached.

In testimony whereof, the signature of the inventor is affixed hereto.

WILLIAM HENRY TROUT.
